OVERHEAD CRANE TROLLEY TURNTABLE

Boris M. Osojnak, Pittsburgh, Pa., assignor to
 Heyl & Patterson, Inc., Pittsburgh, Pa., a corporation of Pennsylvania

Application November 16, 1950, Serial No. 196,010

4 Claims. (Cl. 212—21)

1

This invention relates to turntables for trolleys movable along overhead rails with means on the turntable for operating cables supporting a bucket or the like suspended beneath the trolley, the turntable being turnable on the trolley for rotating the suspended bucket or the like about a vertical axis.

A pair of independently driven cable drums are preferably mounted on such a trolley for the purpose of supporting and operating a bucket or the like, with one motor controlling the vertical movement of the bucket and the other motor acting or cooperating with the first motor to open and close the bucket or to tilt it between carrying and emptying positions. It has been customary to mount the motors for the drums on the same level as the drums in order to expose each drum and motor for servicing. When the motors and drums are mounted on the same level in the conventional manner the area occupied by these parts becomes extensive and it is not practicable to mount the drums and motors on a turntable because the large overhang beyond the rails causes interference with adjacent structures. As a result, it has heretofore been conventional to mount only a single drum and motor on a turntable crane trolley, and this makes it more difficult to operate the suspended bucket or the like than in the case where two cable drums with independently driven motors are used.

In accordance with the invention, the combined advantages of dual drums and motors and of a turntable for rotating the mechanism suspended beneath the trolley are achieved by suspending the trolley between the rails, mounting the turntable closely above the rails with only a slight overhang beyond the width of the rails, and mounting a pair of drums on opposite sides of and close to the turntable axis of rotation, with the motor for each drum mounted thereabove and also close to the axis of turntable rotation. In this way the center of gravity of the assembly on the turntable is brought as close as possible to the level of the rails, the moment of inertia of the assembly on the turntable is decreased, a minimum of top and side clearance is needed for passage of the trolley, and the weight of the whole assembly is reduced to a minimum. A relatively light-weight construction which combines dual motors and drums with a turntable mounting is especially important in the case of a bridge crane with a clamshell bucket for loading and unloading a ship, because such a construction permits flexible operation and at the same time does not require a heavy structure

2

to support the trolley or to prevent the trolley from overrunning its rails and falling on a ship or into the water below. The danger of overrunning may be appreciated when it is realized that such trolleys travel at a rate of about one thousand feet per minute and must be stopped at the end of a cantilever structure supporting the trolley over a ship at about ninety feet above water level. The fact that the motors are mounted over the drums presents a problem in providing access to the drums, but in accordance with the invention this difficulty is overcome by mounting each motor and drum on a multiple frame which has a plurality of separate sections which are normally secured together but which are readily disconnected to remove a motor with a portion of the driving gears to expose the drum therebeneath for repair or replacement. The various sections of the mounting are arranged to hold different halves of split bearing housings for the shafts of the geared drive between each motor and drum in order to facilitate the servicing or removal of the elements connected to the shafts, and the lowermost section is integral with the turntable to provide a strong but light-weight and easily fabricated construction.

Other details, objects and advantages of the invention will become apparent as the following description of a present preferred embodiment thereof proceeds. In the accompanying drawings I have shown, for purposes of illustration only, a present preferred embodiment of the invention, in which:

Figure 1 is a top elevation of a crane trolley incorporating my invention, resting on a broken-away portion of a supporting railed bridge;

Figure 2 is a side elevation corresponding to Figure 1;

Figure 3 is an enlarged top elevation of a portion of the crane trolley;

Figure 4 is a side elevation corresponding to Figure 3; and

Figure 5 is a partial section on the line V—V in Figure 4.

Referring now more particularly to the drawings and initially to Figures 1 and 2, a trolley 10 having a laterally travelling body 11 rests on a pair of spaced parallel rails 12 and 13 of a horizontal overhead bridge 14 with a conventional clam-shell bucket 15 suspended from the crane trolley beneath the rails. The trolley body 11 extends between the rails 12 and 13, and axles 16 and 17 are journaled in upward extensions of the carriage 11 adjacent its opposite ends. 55 Flanged wheels 18 on the axle 16 and flanged

wheels 19 on the axle 17 roll on the rails 12 and 13. Motors 20 and 21 on the trolley body 11 drive the wheels 18 and 19 respectively, and these wheels are controlled by brakes 22 on the rear extensions of the shafts of the motors 20 and 21. Safety members 23 mounted on the four extreme corners of the trolley body 11 extend over the rails 12 and 13 to clear the rails for the wheels 18 and 19.

A horizontal turntable 24 having an outer railed ring 25 of slightly greater diameter than the width of the rails 12 and 13 is mounted closely above the rails 12 and 13 with its vertical axis centered therebetween. Four flanged wheels 26 are journaled in upwardly extending projections from the trolley body 11, and the ring 25 is supported by and rolls on the wheels 26 about the central vertical axis of the turntable 24. The wheels 26 are distributed approximately equidistantly around the periphery of the ring 25 with two of the rollers close to the inner side of the rail 12 and the other two close to the inner side of the rail 13. Lateral movement of the ring 25 is normally opposed by the flanges of the wheels 26 or in emergency by a pair of flanged safety stops 27 mounted on opposite sides of the ring 25 between the rails 12 and 13. The stops 27 extend over an outwardly flanged portion of the ring 25 in order to oppose tilting of the turntable 24, especially when the rate of movement of the trolley in either direction is being sharply changed. A motor 28 mounted on the trolley body 11 and controlled by a brake 29 drives the ring 25 through gearing 30 and a pinion 31 meshing with a toothed flange 32 around the ring 25.

A pair of parallel cable drums 33 and 34 are separately mounted on the turntable 25 on opposite sides of and close to the turntable axis of rotation and with their lower portions enclosed within the ring 25 close to the level of the rails 12 and 13. A set of cables 35 is wound on the drum 33 and connected to the bucket 15 to move the bucket 15 vertically, and a second set of cables 36 are oppositely wound on the drum 34 and are connected to another portion of the bucket 15 in a conventional manner to open and close the bucket in cooperation with the cables 35. The drum 33 is driven by a motor 37 mounted thereabove and the drum 34 is independently driven by a motor 38. The motors 37 and 38 are also disposed close to the turntable axis of rotation.

The motor 37 has a motor shaft 40 having a front extension connected by a disconnectable coupling 41 to a shaft extension 42 on which is keyed a pinion 43. The rear extension of the motor shaft 40 is controlled by a brake 44. A gear 45 keyed on a shaft 46 is driven by the pinion 43, and a pinion 47 keyed on the shaft 46 drives a gear 48 keyed on one end of a shaft 49 projecting axially and integrally from opposite ends of the drum 33.

The housing for the gearing between the drum 33 and motor 37 is divided horizontally into three sections. The top section 50 mounts the upper halves of two split bearing housings over the shaft 42 on both sides of the pinion 43, and is detachably secured by bolts to a lower section 51 which mounts the other halves of said split bearing housings for the shaft 42. The section 51 also mounts the upper halves of two split bearing housings for the opposite ends of the shaft 46, and is detachably secured to another section 52 therebelow which mounts the other halves

of the said bearing housings for the shaft 46. The section 52 also mounts the upper halves of two split bearing housings over the shaft 49 on both sides of the gear 48, and is detachably secured to a lowermost section 53 which mounts the other halves of the said split bearing housings for the shaft 49. The section 53 is constructed as an integral part of the turntable 24. The rear extension of the drum shaft 49 is journaled in a bearing 54 detachably secured to the turntable 24. A base 55 on which the motor 37 and its brake 44 are mounted has a lower extension at one end resting on and secured to the housing of the bearing 54, and at its other end is detachably secured to the intermediate section 52 of the gear housing. As a result, the motor 37 can be removed with its base 55 secured to the gear housing section 52 and the sections 50, 51 and 52 thereon to expose the drum 33 for repair or replacement.

The drum 34 and motor 38 are mounted in the same way for ready removal or servicing.

The motors are preferably all electric and are controlled from a cab 56 suspended beneath one end of the trolley body 11 (Figure 2). The bucket 15 is flexibly controlled by operating motors 20 and 21 to move the trolley body 11 in either direction along the rails 12 and 13 and thereby move the bucket laterally, by operating the motors 37 and 38 to raise and lower and to open and close the bucket, and by operating the motor 28 to rotate the turntable 24 and thereby revolve the bucket about its vertical axis. The close grouping of the heavy drums and motors on the turntable relative to the axis of rotation of the turntable reduces the rotational inertia and thereby enables a relatively small motor 28 to be used for operating the turntable. At the same time, the mass of the parts mounted on the turntable above the level of the supporting wheels 26 is kept as low as possible so that when the trolley is decelerated by the brakes 22 there is a minimum tendency of the turntable to tip in the direction of travel of the trolley. This is especially important when the bucket 15 is empty and hence there is the least amount of gravitational force holding the turntable assembly on the wheels 26.

While I have shown and described a present preferred embodiment of the invention it will be recognized that the invention is not limited thereto but may be otherwise variously embodied and practiced within the scope of the following claims.

I claim:

1. An overhead crane trolley turntable comprising a body, a plurality of adjacent hoist drums mounted on the body, each drum having a shaft extending therefrom, a plurality of independently operable motors mounted over the respective drums, a driving connection between each drum and its motor, a separate supporting frame for each motor straddling the corresponding drum and removably secured to the body, the body having halves of split bearing housings mounted therein in which the drum shafts are journaled, and the supporting frame for each motor having mounted therein the other halves of the split bearing housings in which the corresponding drum shaft is journaled, whereby each motor with its supporting frame can be lifted off of the drum therebelow to facilitate servicing the drums.

2. An overhead crane trolley turntable comprising a body, a plurality of adjacent hoist

drums mounted on the body, a plurality of independently operable motors mounted over the respective drums, a driving connection between each drum and its motor, and a separate supporting frame for each motor straddling the corresponding drum and removably secured to the body, whereby each motor with its supporting frame can be lifted off of the drum therebelow to facilitate servicing the drums, the drums and motors being substantially entirely disposed within the horizontal confines of the body.

3. An overhead crane trolley turntable comprising a body, a plurality of hoist drums mounted on the body, a plurality of independently operable motors mounted over the respective drums, a driving connection between each drum and its motor, supporting means for each drum forming an integral part of the body and a separate supporting frame for each motor straddling the corresponding drum and removably secured to the supporting means for the drum therebelow, whereby the combined weight of the turntable structure and supporting means for the drums and motors is minimized and the drums are readily accessible for servicing, the drums and motors being substantially entirely disposed within the horizontal confines of the body.

10 5 6 4. An overhead crane trolley turntable comprising a body, a plurality of adjacent hoist drums mounted on the body, a plurality of independently operable motors mounted over the respective drums, a driving connection between each

drum and its motor and supporting frame means for the motors straddling the drums and removably secured to the body, whereby the motors with the supporting frame means therefor can be lifted off of the drums therebelow to facilitate servicing the drums, the drums and motors being substantially entirely disposed within the horizontal confines of the body.
